HYDRAULIC DRIVE FOR INERTIA LOADS

Ransom Tyler, Greenfield, Wis., assignor to The
Oilgear Company, Milwaukee, Wis., a corpora-
tion of Wisconsin

Application April 28, 1948, Serial No. 23,747

7 Claims. (Cl. 60—52)

1

This invention relates to hydraulic drives for inertia loads. The drive to which the invention relates in particular includes a hydraulic motor for driving a load, a pump for supplying motive liquid to the motor to energize it, two fluid channels connecting the pump to the motor and forming therewith a hydraulic circuit, and flow control means for reversing or for starting and stopping the flow of liquid in the circuit to thereby cause the motor to move its load in opposite directions alternately or to start and stop its load intermittently.

For the purpose of illustration, the invention will be explained as being embodied in a drive for reciprocating a saw mill carriage which is adapted to carry a heavy timber past a saw to enable the saw to take cuts from the timber. It is to be understood however, that the invention is not limited to a drive for such use or to a drive for reciprocating a load and that the invention may be embodied in drives for other purposes and in drives which will start and stop loads intermittently.

The flow control means of a hydraulic drive for a saw mill carriage ordinarily is shifted to effect reversal of the carriage when the motive liquid is flowing at a maximum rate from the pump through the first of the two channels to the motor and causing it to drive the carriage at a maximum speed and to discharge liquid at a maximum rate through the second of the two channels to the pump.

The flow control means may be shifted very quickly to divert the motive liquid from the first channel into the second channel but shifting the flow control means does not immediately effect reversal of the carriage for the reason that the inertia of the carriage and the parts movable in unison therewith is so great that a large force and a considerable interval of time are required to decelerate the carriage from maximum speed to zero speed and a corresponding force and interval of time are required to accelerate the carriage from zero speed to maximum speed. Therefore, the carriage will continue to move in the same direction after the flow control means is operated and it will cause the motor to continue to operate in the same direction and to continue to discharge liquid into the second channel until the carriage is decelerated to zero speed. Then the liquid discharged by the pump into the second channel will cause the motor to start the carriage moving in the opposite direction and to gradually accelerate it to maximum speed.

In the prior drives of this kind, the flow con-

2

trol means diverted the motive liquid very quickly from one channel into the channel into which the motor was discharging so that the full volume of the pump and all of the liquid discharged by the motor had to be exhausted through the pump relief valve until the motor was decelerated to zero speed and thereafter liquid was discharged through the relief valve at a rate which gradually decreased from nearly the full pump delivery at zero motor speed to zero at maximum motor speed.

Exhausting liquid through a relief valve causes the oil to become heated and gassified, thereby decreasing the usefulness of the liquid and wasting power. Since the pump relief valve necessarily is set to open at a pressure higher than the normal working pressure, the prior drives could operate only a short time before the liquid became excessively hot and sometimes the liquid became so hot that the drive could not be successfully operated.

The present invention has as an object to provide a drive for inertia loads which may be operated continuously without the motive liquid becoming excessively heated.

Another object is to provide a hydraulic drive capable of reversing or starting and stopping an inertia load without causing any substantial part of the energy stored in the motive liquid to be transformed into heat.

Another object is to provide a hydraulic drive which includes a motor and a variable displacement pump and means for so regulating the displacement of the pump that little if any liquid is exhausted through a relief valve when the motor is started, stopped or reversed.

Other objects and advantages will appear from the following description of the hydraulic drive shown schematically in the accompanying drawing in which the views are as follows:

Fig. 1 is a diagrammatic view of a hydraulic drive in which the invention is embodied.

Fig. 2 is a view of a control linkage, the view being taken on the irregular line 2—2 of Fig. 1 but showing the parts in positions different from those shown in Fig. 1.

For the purpose of illustration, a drive embodying the invention has been shown employed to reciprocate the carriage 1 of a saw mill. Since the saw mill forms no part of the invention, only parts of the carriage have been shown.

Carriage 1 is adapted to be reciprocated by a hydraulic motor 2 which may be of the reciprocating type but which has been shown as being of the rotary type and as being mechanically

connected to carriage 1 by suitable gearing 3 so that, when motor 2 rotates in one direction or the other, it will drive carriage 1 in one direction or the other.

Liquid for energizing motor 2 is supplied thereto by a pump 4 which is continuously driven when the drive is in operation and which is connected to motor 2 by two channels 5 and 6 which form therewith a closed hydraulic circuit. The pressure created by pump 4 in either direction of pump delivery is limited by one or the other of two high pressure relief valves 7 and 8 which have been shown connected between channels 5 and 6. In practice, however, valves 7 and 8 are arranged within the casing of pump 4 and discharge into a base (not shown) which supports pump 4 and constitutes a reservoir from which pump 4 is supplied with liquid.

Pump 4 may be of any suitable type but it has been indicated as being of the general type shown in Patent No. 2,227,814. Since such pumps are well known and in extensive use, it is deemed sufficient to state herein that the pump has its pumping mechanism arranged within a displacement varying member or slide block 9 which is arranged within the casing 10 of the pump, that pump displacement will be zero when slide block 9 is in its central or neutral position, and that the pump will deliver liquid in a direction and at a rate dependent upon the direction and distance slide block 9 is shifted from its neutral position.

Slide block 9 is adapted to be moved upward in respect to the drawing by a piston 11 which engages or is fixed to one side of slide block 9 and is fitted in a cylinder 12 which is formed in the side wall of casing 10 and is closed at its outer end by a cap 13. Cylinder 12 is supplied with operating liquid in which pressure is continuously maintained as will presently be explained.

Slide block 9 is adapted to be moved downward in respect to the drawing by a piston 14 which is larger than piston 11 and engages or is fixed to the opposite side of slide block 9. Piston 14 is fitted in a cylinder 15 which is formed in the side wall of casing 10 and is closed at its outer end by a head 16 having a bore 17 formed therein in axial alignment with a bore 18 which extends through piston 14 and through an extension or hub 19 formed upon the outer face of piston 14. The inner end of bore 18 communicates at all times with the interior of casing 10 as by means of a slot 20 formed in slide block 9.

Liquid is adapted to flow into and out of cylinder 15 through a port 21 which extends through the wall of hub 19 into communication with bore 18. Port 21 is controlled by a rotary valve 22 which is closely fitted in bores 17 and 18 and has two spiral grooves 23 and 24 formed in its periphery at opposite sides of port 21 and spaced apart a distance equal to the diameter of port 21.

One end of groove 23 extends to the end of valve 22 so that groove 23 is at all times in communication with the inner end of bore 18. Groove 24 communicates with one end of an internal passage 25 which extends through valve 22 and has its other end in communication with an annular groove 26 which is formed in the wall of bore 17.

Liquid for energizing servo-motors 11-12 and 14-15 is supplied by a gear pump 30 which for the purpose of illustration has been shown outside of casing 10 but which in practice is arranged within casing 10 and is driven in unison with pump 4.

Gear pump 30 draws liquid through a channel

31 from the base or reservoir of pump 4 and discharges it into a supply channel 32 which has one end thereof connected to end head 16 in communication with groove 26 and the other end thereof connected through a pressure responsive valve 33, to be presently described, and a channel 34 to cylinder 12. Gear pump 30 discharges liquid at a rate in excess of requirements and the excess liquid is exhausted through a low pressure relief valve 35 and a channel 36 into the base of pump 4 so that pump 30 maintains in channel 32 a pressure equal to the resistance of relief valve 35.

The arrangement is such that, when valve 22 is rotated in one direction, groove 24 will open to port 21 and then gear pump liquid will flow from channel 32 through groove 26, passage 25, groove 24 and port 21 into cylinder 15. Since piston 14 is larger than piston 11, the liquid entering cylinder 15 will cause piston 14 to move slide block 9 and piston 11 downward in respect to the drawing and piston 11 will eject liquid from cylinder 12 through channel 34 and valve 33 into channel 32. Piston 14 will continue to move slide block 9 downward until port 21 moves out of communication with groove 24 or until slide block 9 reaches the limit of its movement. Moving slide block 9 downward below its neutral position causes pump 4 to discharge liquid into channel 6.

When valve 22 is rotated in the opposite direction, groove 23 will open to port 21 so that liquid can escape from cylinder 15. Then the gear pump liquid continuously supplied to cylinder 12 will cause piston 11 to move slide block 9 and piston 14 upward in respect to the drawing and piston 14 will eject liquid from cylinder 15 through port 21, groove 23, bore 18 and slot 20 into casing 10 from whence the oil drains into the base of pump 4. Piston 11 will continue to move slide block 9 upward until port 21 moves out of communication with groove 23 or until slide block 9 reaches the limit of its movement. Moving slide block 9 upward above its neutral position causes pump 4 to discharge liquid into channel 5.

Valve 22 may be rotated either manually or in response to carriage 1 reaching a given position during its movement in each direction. As shown, valve 22 is adapted to be rotated by a lever 40 which is fixed to the outer end thereof and which also restrains valve 22 from axial movement. The free end of lever 40 has a slidable pivotal connection with one arm of a bell crank lever 41 which is pivoted upon a stationary shaft 42. The other arm of lever 41 is connected by an adjustable link 43 to a lever 44 which is fixed upon a shaft 45 mounted in suitable bearings one of which is indicated at 46.

Shaft 45 is adapted to be rotated in one direction or the other either by a hand lever 47 fixed thereon or by one or the other of two reversing ears 48 and 49 which are fixed upon shaft 45 and adapted to be operated, respectively, by two dogs 50 and 51 which are fixed to carriage 1 in adjusted positions.

Valve 22 ordinarily is rotated almost instantly from one position to another regardless of whether it is rotated manually or is rotated in response to carriage 1 reaching a given position. If no means were provided for limiting its rate of movement, slide block 9 would move almost as fast as valve 22 was rotated and would vary the rate of delivery of liquid from pump 4 so rapidly that large volumes of liquid would be exhausted through relief valves 7 and 8 as explained above.

In a drive embodying the present invention, slide block 9 can move freely until the pressure

in one or the other of channels 5 and 6 is nearly high enough to open the relief valves 7 or 8 connected to the channel 5 or 6 containing the high pressure. Then the pressure in that channel will cause valve 33 to throttle the flow of liquid into or out of cylinder 12 and thereby limit the rate at which slide block 9 can move.

As shown, valve 33 includes a valve body 55 having an axial bore 56 in the central portion thereof, two annular grooves or ports 57 and 57^a formed in the wall of bore 56 and two counterbores or pressure chambers 58 and 58^a arranged at opposite ends of bore 56 concentric therewith. Ports 57 and 57^a have channels 32 and 34 connected thereto respectively. Pressure chambers 58 and 58^a are connected to channels 5 and 6, respectively, by two channels 59 and 60.

Communication between ports 57 and 57^a is adapted to be restricted or interrupted by a piston valve 61 which is slidably fitted in bore 56. The right hand end of valve 61 is engaged by a spring retainer 62 which normally is held against the annular end wall of chamber 58 by a spring 63 and which has a passage 64 extending therethrough so that liquid can flow freely between chamber 58 and the adjacent end portion of bore 56. The tension of spring 63 may be adjusted by means of shims inserted between its outer end and the outer end wall of chamber 58 but it has been shown as engaging a spring retainer 65 which is engaged by an adjusting screw 66 threaded through the end wall of chamber 58.

Since the two halves of valve 33 are identical, further description is deemed unnecessary as like parts have been indicated by the same reference numerals with the exponent "a" added to the reference numerals applied to the parts in the left hand half of valve 33.

Operation

With the parts in the positions shown in Fig. 1 and with pumps 4 and 30 running, pump 4 is at zero stroke so that no liquid is being discharged thereby and pump 30 is discharging through channel 32, relief valve 35 and channel 36 into the base of pump 4.

Assuming that carriage 1 has a heavy load arranged thereon and that it is to be reciprocated for a period of time after being started moving toward the left in respect to the drawing, the drive will operate as follows:

The drive may be started by swinging hand lever 47 upward, as indicated in Fig. 2, which will cause valve 22 to be rotated in a direction to open spiral groove 24 to port 21. Then gear pump liquid will flow from channel 32 through groove 26, passage 25, groove 24 and port 21 into cylinder 15 and cause piston 14 to move slide block 9 downward, thereby causing pump 4 to deliver liquid through channel 6 to motor 2 to energize it.

Slide block 9 will start to move and cause pump 4 to start to deliver liquid substantially as soon as valve 22 starts to rotate. The rate at which slide block 9 moves and the rate at which pump 4 discharges liquid will increase at substantially the rate at which valve 22 is rotated but, due to the inertia of carriage 1 and the parts movable therewith, motor 2 cannot start until pump 4 has created a high pressure and it cannot accelerate as fast as the delivery of pump 4 increases.

Pump 4 thus tends to deliver liquid faster than the liquid can enter motor 2 which causes pressure to rise in channel 6 and, when the pressure becomes high enough, motor 2 will start but pump 4 continues to tend to deliver liquid faster than

the liquid can enter motor 2 so that the pressure continues to rise until it reaches a predetermined maximum which is determined by the resistance of spring 63 and which is a little lower than the pressure required to open relief valve 8. Then liquid will flow from channel 6 through channel 60, pressure chamber 58^a and passage 64^a into bore 56 and move valve 61 toward the right against the resistance of spring 63.

Moving valve 61 toward the right restricts port 57^a and reduces the rate at which liquid can escape from cylinder 12, thereby restricting the movement of slide block 9 and reducing the rate at which pump delivery increases. If lever 47 is operated very suddenly as is customary, pump delivery may increase so rapidly and pressure may rise so suddenly and so high that valve 61 would be moved far enough to completely close port 57^a and thereby stop further movement of slide block 9 and further increase in pump delivery until motor 2 is started and then the pressure would drop slightly and permit spring 63 to move valve 61 far enough toward the left to partly open port 57^a so that liquid could escape from cylinder 12 at a limited rate and permit piston 15 to move slide block 9 downward to increase pump delivery at the rate required to maintain the maximum pressure in channel 6.

Since the force required to start and accelerate a load is greater than the force required to keep the load moving after it has been accelerated to a given speed, slide block 9 will move downward and increase the delivery of liquid from pump 4 at the rate required to maintain the maximum pressure in channel 6 until motor 2 has been accelerated to its running speed and then the pressure will drop and permit spring 63 to move valve 61 to its central position.

The pressure created by the pump is thus maintained at a predetermined maximum so that the time required to accelerate carriage 1 to running speed is reduced to a minimum without causing a large volume of liquid to be exhausted through a relief valve as would be the case if movement of displacement varying member were not controlled in response to pump pressure reaching a predetermined maximum.

Motor 2 will drive carriage 1 toward the left at high speed until shaft 45 is rotated counterclockwise in respect to Fig. 2 either by hand lever 47 being moved downward manually or by dog 50 engaging reversing ear 48 and swinging it toward the left.

Rotating shaft 45 counterclockwise causes valve 22 to be rotated in a direction to open spiral groove 23 to port 21 so that liquid can escape from cylinder 15 and permit the gear pump liquid supplied to cylinder 12 to cause piston 11 to start moving slide block 9 upward to thereby start reversing pump 4.

Slide block 9 will start to move substantially as soon as valve 22 starts to rotate and it will very quickly reduce the rate of pump delivery below the rate required to keep motor 2 operating at its current speed but, due to the inertia of carriage 1 and the parts movable therewith, motor 2 will continue to operate in the same direction and continue to discharge liquid through channel 5 to pump 4.

Slide block 9 will tend to reduce pump displacement to such an extent that all of the liquid discharged by motor 2 cannot enter pump 4, thereby causing motor 2 to create pressure in channel 5.

Since the energy which enables motor 2 to create pressure in channel 5 is derived from car-

riage 1, motor 2 acts as a brake upon carriage 1 to quickly decelerate it to zero speed.

The pressure created by motor 2 will continue to rise until it reaches a predetermined maximum which is determined by the resistance of spring 63^a and which is a little lower than the pressure required to open relief valve 7. Then liquid will flow from channel 5 through channel 59, pressure chamber 58 and passage 64 into bore 56 and move valve 61 toward the left against the resistance of spring 63^a.

Moving valve 61 toward the left restricts port 57 and reduces the rate at which liquid can enter cylinder 12, thereby restricting the upward movement of slide block 9 and reducing the rate at which pump delivery is reduced. Since valve 61 is operated by the pressure in channel 5, it will limit the flow of liquid into cylinder 12 to the rate necessary to enable piston 11 to reduce pump displacement just fast enough to cause motor 2 to maintain the predetermined maximum pressure in channel 5 until motor 2 is decelerated substantially to zero speed.

When motor 2 reaches zero speed, piston 11 will have moved slide block 9 far enough to cause pump 4 to start discharging liquid into channel 5. Since the movement of slide block 9 is controlled by the pressure in channel 5, pump 4 will maintain the same maximum pressure in channel 5 so that the instant that carriage 1 stops moving toward the left motor 2 is exerting sufficient torque to start its moving toward the right.

Motor 2 will gradually accelerate carriage 1 and piston 11 will continue to move slide block 9 just fast enough to enable pump 4 to maintain the predetermined maximum pressure in channel 5 until motor 2 approaches its running speed and then, since the force required to keep carriage 1 moving at a given speed is less than the force required to accelerate it to that speed, the pressure in channel 5 will drop and permit spring 63^a to return valve 61 to its central position.

Motor 2 will drive carriage 1 toward the right at high speed until shaft 45 is rotated clockwise in respect to Fig. 2 either by hand lever 47 being moved upward manually or by dog 51 engaging reversing ear 49 and swinging it toward the right. Rotating shaft 45 clockwise causes valve 22 to be rotated in a direction to open spiral grooves 24 to port 21 so that liquid can enter cylinder 15 and cause piston 14 to start moving slide block 9 downward. Then the drive will be reversed in the manner described above except that slide block 9 will be moved downward, motor 2 will discharge liquid into channel 6 while being decelerated, pump 4 will discharge liquid into channel 6 after motor 2 has been decelerated to zero speed, and the pressure in channel 6 will cause valve 61 to throttle the flow of liquid out of cylinder 12 as slide block 9 moves downward.

Motor 2 will continue to drive carriage 1 in opposite directions alternately until valve 22 is rotated to its neutral position as shown in Fig. 1 which will cause slide block 9 to return to its neutral position. Slide block 9 will start to move as soon as valve 22 starts to rotate but carriage 1 will continue to move and to drive motor 2 which will create pressure to enable it to exert a brake load upon carriage 1 and to cause valve 61 to shift far enough to restrict the flow of liquid into or out of cylinder 12 and thereby limit the movement of slide block 9 to the rate required to enable motor 2 to create pressure until it stops.

When the pump or motor is creating pressure

in one side of the circuit, there is insufficient liquid in the other side of the circuit to supply the pump or motor which is creating the pressure but this deficiency is made up by liquid supplied to the low pressure side of the circuit either directly from the reservoir or by gear pump 30 through one or the other of two check valves one of which is connected to either side of the circuit and which permits liquid to flow into the circuit but prevents flow in the opposite direction. Since such an arrangement is well known and in extensive use, it has been omitted from the drawing in order to avoid complicating the view.

If the displacement varying member of the pump were permitted to move freely in a drive for inertia loads as is customary in the prior drives of this character, the pump would exhaust liquid through a relief valve while the load was being started and being accelerated to running speed, the motor would exhaust liquid through a relief valve while the load was being stopped, and during reversal both the pump and the motor would exhaust through a relief valve while the load was being decelerated to zero speed and then the pump would exhaust liquid through a relief valve while the load was being accelerated to running speed. A drive embodying the present invention is capable of starting, stopping and reversing an inertia load just as quickly as the prior drives but substantially no liquid is exhausted through the relief valves.

The invention herein set forth is susceptible of various modifications and adaptations without departing from the scope thereof which is hereby claimed as follows:

1. A hydraulic drive comprising a hydraulic motor for driving an inertia load, a pump for supplying motive liquid to said motor to energize the same and having a displacement varying member movable to and from a neutral position to vary the rate of pump delivery, fluid channels connecting said pump to said motor and forming therewith a hydraulic circuit, hydraulic servo-motor means for moving said displacement varying member, means supplying operating liquid to said servo-motor means, a first valve for controlling the operation of said servo-motor means, and a second valve operable in response to the pressure in said circuit reaching a predetermined maximum for limiting the rate at which said servo-motor means can move said displacement varying member.

2. A hydraulic drive comprising a hydraulic motor for driving an inertia load, a pump for supplying motive liquid to said motor to energize the same and having a displacement varying member movable to and from a neutral position to vary the rate of pump delivery, fluid channels connecting said pump to said motor and forming therewith a hydraulic circuit, hydraulic servo-motor means for moving said displacement varying member, means supplying operating liquid to said servo-motor means, a first valve for controlling the operation of said servo-motor means, and a second valve operable in response to the pressure in either side of said circuit reaching a predetermined maximum for further controlling said servo-motor means to thereby limit the rate of movement of said displacement varying member.

3. A hydraulic drive comprising a hydraulic motor for driving an inertia load, a pump for supplying motive liquid to said motor to energize the same and having a displacement vary-

ing member movable in opposite directions from a neutral position to vary the rate and direction of pump delivery, fluid channels connecting said pump to said motor and forming therewith a hydraulic circuit, servo-motor means for moving said displacement varying member, and means responsive to the pressure in either side of said circuit reaching a predetermined maximum for limiting the rate of movement of said member.

4. A hydraulic drive comprising a hydraulic motor for driving an inertia load, a pump for supplying motive liquid to said motor to energize the same and having a displacement varying member movable in opposite directions from a neutral position to vary the rate and direction of pump delivery, fluid channels connecting said pump to said motor and forming therewith a hydraulic circuit, hydraulic servo-motor means for moving said displacement varying member, means for supplying operating liquid to said servo-motor means, a first valve for controlling the operation of said servo-motor means, and a second valve operable in response to the pressure in said circuit reaching a predetermined maximum for limiting the rate at which said servo-motor means can move said displacement varying member.

5. A hydraulic drive comprising a hydraulic motor for driving an inertia load, a pump for supplying motive liquid to said motor to energize the same and having a displacement varying member movable to and from a neutral position to vary the rate of pump delivery, fluid channels connecting said pump to said motor and forming therewith a hydraulic circuit, a large servo-motor for moving said member in one direction, a small servo-motor for moving said member in the opposite direction, a source of operating liquid, means including a valve for connecting said large servo-motor to said source and to exhaust alternatively, and means for connecting said small servo-motor to said source including a valve operable in response to the pressure in said circuit reaching a predetermined maximum for throttling the flow of liquid into and out of said small servo-motor.

6. A hydraulic drive comprising a hydraulic motor for driving an inertia load, a pump for supplying motive liquid to said motor to energize the same and having a displacement varying member

10 15 20 25 30 35

movable to and from a neutral position to vary the rate of pump delivery, fluid channels connecting said pump to said motor and forming therewith a hydraulic circuit, a large servo-motor for moving said member in one direction, a small servo-motor for moving said member in the opposite direction, a source of operating liquid, means including a valve for connecting said large servo-motor to said source and to exhaust alternatively, and means for connecting said small servo-motor to said source including a valve operable in response to the pressure in either side of said circuit reaching a predetermined maximum for throttling the flow of liquid into and out of said small servo-motor.

7. A hydraulic drive comprising a hydraulic motor for driving an inertia load, a pump for supplying motive liquid to said motor to energize the same and having a displacement varying member movable in opposite directions from a neutral position to vary the rate and direction of pump delivery, fluid channels connecting said pump to said motor and forming therewith a hydraulic circuit, a large servo-motor for moving said member in one direction, a small servo-motor for moving said member in the opposite direction, a source of operating liquid, means including a valve for connecting said large servo-motor to said source and to exhaust alternatively, and means for connecting said small servo-motor to said source including a valve operable in response to the pressure in either side of said circuit reaching a predetermined maximum for throttling the flow of liquid into and out of said small servo-motor.
